UNITED STATES PATENT OFFICE.

TOBIAS SVENSON, OF MILWAUKEE, WISCONSIN.

SELF-CLEARING PROPELLER.

1,390,397.

Specification of Letters Patent. Patented Sept. 13, 1921.

Application filed December 6, 1920. Serial No. 428,517.

To all whom it may concern:

Be it known that I, TOBIAS SVENSON, a citizen of the United States, and resident of Milwaukee, in the county of Milwaukee and State of Wisconsin, have invented certain new and useful Improvements in Self-Clearing Propellers; and I do hereby declare that the following is a full, clear, and exact description thereof.

10 My invention relates to means adapted to be applied upon the submerged portion of a motor which is used as the propelling means for a boat of any desired structure, and it is particularly adapted for use upon motors of the portable type.

Heretofore, in weedy water, particularly marshes, where bulrushes, sea-weeds or other floating or suspended vegetation is found, it has been impossible to successfully navigate 20 boats driven by rotary propellers, due to the fact that the undergrowth winds upon the propeller or shaft, which invariably causes the propeller or shaft to break, or it may cause the engine to stop.

25 Therefore, the main object or purpose of my invention is to provide means which may be applied to a motor of the character set forth which will cut from the propeller or its shaft any vegetation that may become 30 gathered thereupon.

A further object of my invention is to provide a cutting element actuated by the rotation of the propeller shaft and coacting with certain stationary means which will sever 35 any material retained by the propeller or its shaft.

It is also an object of my invention to provide means that will assist in bringing the vegetation which may gather upon the shaft 40 in such a position that it will be cut therefrom by the cutting element.

A further object of my invention is to provide means between the casing of the propeller driving shaft and the propeller that will 45 coöperate with the edges of the latter for the purpose of cutting therefrom any vegetation that may be gathered thereby as it travels toward the propeller shaft.

From the objects set forth, it will be apparent that as the propeller revolves any vegetation gathered thereupon, or its shaft, will be cut as it is brought in contact with the cutting elements, thereby preventing it

from winding about the shaft to such a degree that damage will be caused.

55 In the accompanying drawings:

Figure 1 is a side elevation of a propeller and its operating means with my invention applied thereto, same being shown partly in section.

60 Fig. 2 is a rear view of the same.

Fig. 3 is a section on the line 3—3 of Fig. 1.

Fig. 4, a front view of the means applied between the casing and the propeller, and

65 Fig. 5 is a detail view of the cutting element.

Referring to the drawings in detail, the letter A designates the rotary propeller of the motor, same being secured to and rotated by the horizontal shaft B, the latter being in gear connection with the vertical shaft C, the upper end of which is connected with the motor and rotated thereby. The shafts B and C are suitably housed in a casing, the lower part of which has made integral therewith the rudder D, while the upper part has secured thereto by the screws E, the tubular sleeve F, in which the upper part of the shaft C is housed. The structure herein described is common in that type of motor previously referred to, and therefore, I do not limit myself to this structure.

My invention comprises the following structure, or its equivalent; secured upon the exterior of the tubular sleeve F, and by one of the sleeve securing screws E, is a plate 1 the body of which is curved, while one end portion is bent at substantially right angles to the plate, as indicated at 2, said bent portion lying in a vertical plane extending through the center of the shaft C. The lower end portion of the member 2 extends downward and is adapted to rest upon the casing, as shown in Figs. 1 and 2, and has made integral therewith the shearing block 3, one side of which is inclined while the other is vertical and the latter being adapted to coöperate with a movable cutting element, which will be described more fully hereinafter.

90 The shaft B has secured thereto or made integral therewith adjacent its connection with the shaft C, the cam 4 upon the periphery of which rests the operating element of 95 100 105 the cutter.

The casing of the driving elements for the propeller A has fitted therein, above the cam 4, a tubular sleeve 5, same being held to the casing by the screw 6. Movable within the sleeve 5 and operated by the cam 4, is a piston or plunger 7 the upper end of which has made integral therewith the ring 8, same being adapted to slide up and down on the sleeve F as the plunger 7 is moved.

10 The ring 8 has secured thereto diametrically opposite the plunger 7 the vertical extending plate 9, the lower end of which is provided with an outwardly extending portion, the upper edge of which is sharpened, 15 as indicated at 10. The plate 9 has provided therein the elongated slot 11, through which passes the bolts 12, same being adapted to hold the cutter in place between the plates 2 and 13, and also act as a guide therefor.

20 As shown in Fig. 5, I have provided the edge of the cutting plate 9, that adjacent the sleeve F and opposite to the cutting edge, with a small curved portion 16 same extending the full length of the plate, the purpose 25 of which is to guide the cutter properly in its operation and to assist in holding the plate 1 in its proper position.

As I have shown in the drawings, the shearing block 3 extends longitudinally of the casing to such a position that its edge lies beyond the edge of the casing, as shown in Fig. 1. Mounted upon the bearing of the shaft B is a circular plate 14 the edge of which is provided with a plurality of fingers 35 15 the upper edge of which are slightly curved. These fingers are adapted to lie in a plane parallel to that of the plate proper and are connected therewith by the web 17, the latter being so arranged that the fingers 40 will be free to move between the block 3 and the propeller blades. In applying the plate in its proper position, one of the fingers is so positioned with respect to the block 3 that as the propeller revolves any vegetation 45 caught thereby will be carried up over the block, so as to lie in a position to be severed as the cutter moves upward. Furthermore, the fingers 15 serve as a cutting or shearing element in conjunction with the edges of the 50 propeller blades as the latter revolves, and any material caught thereby will be cut, or a portion thereof, before it reaches the propeller shaft.

As will be apparent from the foregoing 55 description, the operation of the attachment is as follows: as the shaft B rotates the movable cutting element 9 will be moved upward and any material upon the block 3 will be cut by the sharpened edge 10 thereof. It 60 will be understood that the plate is moved up and down by the plunger 7 which is in contact with the cam 4 on the shaft B. Then as the propeller revolves any vegetation caught thereby will be cut either be- 65 tween the fingers 15 and the edges of the propeller blades or by the reciprocating cutter.

This operation applies whether in moving forward or reversing. Weeds or any material that might otherwise wind about the shaft will be severed by the fingers 15 before it reaches the shaft. Should it not be cut by this means, it will then be cut by the reciprocating cutter.

From the foregoing, it is thought that the construction, operation and many advantages of the herein described invention will be apparent to those skilled in the art, without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is:—

1. In a device of the character described, the combination of a propeller and its shaft, movable means operated by the latter, and stationary means coacting with said movable means and the propeller for severing material.

2. In a device of the character described, a propeller and a shaft for operating same, a reciprocating cutter operated by the latter 95 and a stationary cutter coacting with the former for severing material.

3. In a device of the character described, a reciprocating cutter operated by a cam secured to a rotary element and a stationary 100 cutter coacting with the blades of a propeller to cut material.

4. In a device of the character described, the combination of a closed casing, a propeller shaft extending rearward therefrom 105 and a propeller thereon, a reciprocating cutter operated by said shaft, and a second cutter positioned between the casing and the propeller and adapted to coact with the latter, and both cutters operating to sever material gathered by the propeller or its shaft.

5. In a device of the character described, the combination of a closed casing, a propeller shaft extending rearward therefrom and a propeller mounted thereon, a stationary cutting element on the casing, a movable cutting element operated by the shaft and coacting with the stationary element, a second stationary member positioned between the casing and the propeller and both cutters 115 operating to sever material gathered by the propeller or its shaft.

6. In a device of the character described, the combination of a closed casing having therein a vertical shaft and a horizontal 125 shaft, a propeller on one end thereof and a cam adjacent the other end, a cutting element secured to the casing and coacting with a second cutting element movable thereon and operated by said cam, a plate positioned 130

between the casing and the propeller and having fingers adapted to coact with the stationary cutting element and to sever material caught between them and the edges

5 of the propeller blades.

7. In a device of the character described, the combination of a casing and a propeller, a shearing block secured to said casing, a movable cutter coacting therewith, means

10 positioned between the casing and the pro-

peller and adapted to carry gathered material over said shearing block and to cut material caught between it and the propeller blades.

In testimony that I claim the foregoing I 15 have hereunto set my hand at Milwaukee, in the county of Milwaukee and State of Wisconsin.

TOBIAS SVENSON.
